UNITED STATES PATENT OFFICE.

EBENEZER WOODBURY GERRISH, OF JACKSONVILLE, FLORIDA.

LOG HAULING AND LOADING MACHINE.

No. 897,613.

Specification of Letters Patent.

Patented Sept. 1, 1908.

Application filed February 24, 1905. Serial No. 247,205.

To all whom it may concern:

Be it known that I, EBENEZER WOODBURY GERRISH, a citizen of the United States, and a resident of Jacksonville, Duval county, and 5 State of Florida, have invented a new and useful Improvement in Log Hauling and Loading Machines, of which the following is a specification.

In practice, I have applied my invention 10 to a log hauling and loading machine of the general character described in Patent No. 726325 dated April 28, 1903, to Thomas Spencer Miller and Joseph H. Dickinson.

In the accompanying drawings, Figure 1 is 15 a side view of a machine embodying my invention. Fig. 2 is a plan view of the same minus the upper structure. Figs. 3 and 4 are details. Fig. 5 is a detail view showing the drum for operating the suspender.

20 A is a platform or frame of any suitable construction which will give sufficient space and strength to hold the machine and to be carried when in use by supports at each side of the track sufficiently separated to permit 25 the passage of cars between them. Upon this platform is mounted the hoisting or hauling engine necessary to work the required lines and a boiler or boilers to furnish steam for them, as well as the mast and 30 boom. Longitudinal sills a are placed beneath each side of the platform and to each of these are secured blocks a' at each end of the platform. B are beams resting on the ends of the ties outside of the rails C.

35 b are blocks interposed between each of the beams B and the two blocks a' above it.

D are hydraulic jacks each interposed between a sill a and a block E resting on a beam B. The construction of each of these 40 jacks is shown in Fig. 4. The upper part consists of a cylinder d and the lower part of a plunger d'. The cylinder is supplied with water from the water barrel F by the pump G through the piping shown. Connected 45 with this system of piping is a relief valve H set to relieve all pressure beyond a certain point.

I is a safety vent in the cylinder to permit the escape of the water when the plunger has 50 been forced downward beyond a given point.

J is a suspender for the lower plunger portion d' of the jack, which suspender is coiled

upon a drum j operated by the handle j' and held in any desired position by the ratchet j² and pawl j³. The supply piping to each jack 55 is provided with a three-way-valve K and a cut-off-valve L.

The machine operates as follows: The platform A is brought to any desired position when loaded upon an ordinary car. The 60 beams B, blocks E and jacks D are then placed in position and the platform is raised off of the car by the operation of the jacks. This enables the blocks b to be placed under the blocks a'. Then the jacks are operated 65 to permit the lowering of the blocks a' onto the blocks b. After this lowering, however, the platform A is still high enough to permit the passage of cars beneath.

In the operation of the jacks for raising, 70 the three-way-valve K is set so as to cut off the discharge of water and permit its passage through the piping, and the valve L is opened. When the hydraulic jacks are operated for lowering, the three-way-valve 75 K is turned so as to discharge the water from the piping through the escape k and the cut-off-valve L is closed.

When the machine is loaded upon a car for 80 transportation, the cylinder or upper portion d of the jack will be held to the sill a by being bolted permanently thereto as by the bolts d². The plunger portion of the jack will be held in position by the suspender J, which suspender, of course, is released while the 85 jack is being hydraulically operated.

Having thus described my invention, what I claim as new is,

In a log hauling machine, in combination, the engine-supporting-platform, legs therefor adapted to straddle the railway track, hydraulic jacks coöperating with said legs and a pump mounted upon said platform whereby said jacks are operated, and a suspender whereby the lower member of each 90 95 of said jacks is suspended when not in operation.

In testimony whereof, I have hereunto signed my name in the presence of two subscribing witnesses.

E. WOODBURY GERRISH.
